LINK CHAIN FOR A BRACELET OR THE LIKE

Walter J. Luft, Forest Hills, N.Y., assignor to Jacoby-Bender, Inc., Woodside, N.Y., a corporation of New York

Filed July 26, 1967, Ser. No. 8,000

Term of patent 7 years

(Cl. D45—4)

FIG. 1

FIG. 2

FIG. 3

FIG. 4

FIG. 1 is a top plan view of a link chain for a bracelet showing my new design;

FIG. 2 is a side elevational view on an enlarged scale of the shell of one of the individual links of FIG. 1;

FIG. 3 is an end elevational view of the link of FIG. 2; and

FIG. 4 is a three-quarter perspective view of the link of FIG. 2.

The essential features of the design reside in the portions shown in full lines.

I claim:

The ornamental design for a link chain for a bracelet or the like, as shown and described.
